UNITED STATES PATENT OFFICE

ADELA MARY GRAY KEYS, OF LONDON, ENGLAND

DEVICE FOR DRYING OR AIRING GARMENTS OR OTHER ARTICLES

Application filed October 2, 1928, Serial No. 309,845, and in Great Britain October 6, 1927.

My invention relates to that class of device employed for drying or airing garments, linen and other articles, which serves as a clothes-horse or support and is arranged in 5 a position above or on the top of a portable or other stove used for heating, cooking or for similar purposes.

The invention consists in an improved construction and arrangement of such a device 10 which may be of any required size. According to the invention, the improved drying or airing device, which is preferably made of metal, has an upright body part of cylindrical or other tubular form, the lower portion 15 of the body being detachably supported on the upper part or top of the stove with which the device is associated. The bottom end of the body is open, but its upper end is closed by a cap piece which may be in one 20 with or be attached to or engaged with the body. The body may consist of a single member or a number of members which may be hinged or otherwise connected together so as to permit of the body being collapsed or folded 25 when not in use.

The cap piece may be circular or of other desired configuration and may be domed or flat on the top and be provided with or without fin-like or other appropriately shaped 30 projecting parts on its upper surface. It may be of such a size that marginal portions thereof of overhang the rim or mouth of the body so that portions of garments or other articles placed on the cap piece can be suspended 35 around the body without touching it and without risk of being scorched.

The side wall or walls of the tubular body 40 may be of wire or wire netting, which may be enamelled, painted, or otherwise rendered smooth. Alternatively, the walls may be formed of other appropriate foraminous material such as sheet metal plate, or consist in whole or part of asbestos or like substance. 45 The side wall or walls may consist of one or

more thicknesses or layers of the netting or other material used.

The improved drying or airing device may be attached to an associated stove by means of pin and slot or pin and eyelet connections, 50 or by means of clips or in any other convenient known manner. If desired, the device may be fitted with legs for supporting from the ground, in addition to or in place of the above-mentioned supporting means. 55

The invention is illustrated in the annexed drawings, in which:—

Fig. 1 is an elevation of the drying device attached to a stove, the cap piece or cover member being shown separately. 60

Fig. 2 is a plan with the cover member removed, and

Fig. 3 is a detail view with the cover member turned upside down.

In these drawings, *a* represents the body 65 of the drying device, which as shown may consist of a cylindrical upright member formed of wire. The cap piece or cover member *b* is preferably formed of the same material as, but is of larger diameter than, 70 the member, *a*, in order that articles suspended from it do not come into contact with the member *a*. The latter is fitted over the upper portion of a stove *c* by means of the legs *d*, which are made of some material 75 adapted to be somewhat expanded radially so that the legs may adapt themselves to variations in size in the circumference of the stove.

The cover member *b* may be made convex 80 in shape and may be reversed as shown in Fig. 3 so that the concave surface faces upwards. The legs *d* serve to support the device on the ground when not in use.

What I claim is:—

A drier comprising a vertical frame, a foraminous body portion surrounding the vertical frame, the frame having legs extended from its bottom to engage over a stove when the drier is in use, or form a 90

support when out of use, a concavo-convex foraminous cap on top of the frame, said cap being of greater diameter than the horizontal diameter of the frame, and extending 5 beyond the latter, the foraminous cap adapted to be seated on top of the frame to form either a concave receptacle for the goods being dried or inverted to form a convex support for goods to be dried, in either position 10 said cap being retained in position by the roughened portions of the foraminous material interlocking with the edge of the corresponding portions of the foraminous material surrounding the vertical frame.

15 In testimony whereof I have hereunto signed my name.

ADELA MARY GRAY KEYS.
